UNITED STATES PATENT OFFICE.

GOTTFRIED F. GASSER, OF ATLANTA, GEORGIA, ASSIGNOR TO ANNIE GASSER, OF ATLANTA, GEORGIA.

BURGLAR-ALARM SYSTEM.

Application filed December 15, 1922. Serial No. 607,049.

To all whom it may concern:

Be it known that I, GOTTFRIED F. GASSER, a citizen of the United States, residing at Atlanta, in the county of Fulton and State 5 of Georgia, have invented a certain new and useful Improvement in Burglar-Alarm Systems, of which the following is a full, clear, and exact description, reference being had to the accompanying drawings.

10 This invention relates to combined burglar and fire alarm systems.

My invention is embodied in the provision of a system which may be used as a burglar or fire alarm comprising the use of a normally closed circuit, and two normally open circuits, an alarm in one of the normally open circuits and a common source of electrical supply for all of said circuits. The invention contemplates the arrangement of 15 the circuits in such manner that the opening of the closed circuit or the closing of the open circuit actuates the alarm.

In addition, my invention provides for a cabinet wherein the various controls may 20 be centrally located, and wherein suitable test switches may be mounted for enabling an authorized person to determine the exact 25 circuit or loop in which the break or short circuit has occurred. This is particularly 30 advantageous in that, the exact loop, or station, may be quickly ascertained and the source of difficulty remedied in the most expeditious manner.

Other characteristics of my invention are 35 embodied in suitable safety devices for permitting the disconnection of the system for repairs or other adjustments without sounding the alarm, and for preventing the surreptitious handling of the controls when 40 the system is in working order.

The particular arrangement of the various devices for carrying out the objects 45 of my invention will be hereinafter more fully set forth in the following description, which pertains to the accompanying drawings, and the essential features will be summarized in the claims.

In the drawings, Fig. 1 is an elevation of 50 two windows having loops thereon forming part of a circuit system embodying my invention; Fig. 2 is a vertical section through a cabinet having devices therein for operating the system; Fig. 3 is a wiring diagram for connecting the apparatus shown in Fig. 2.

55 My invention is particularly directed to-

ward the use of a normally closed circuit, the opening of which sounds an alarm in a normally open circuit. Accordingly, in Fig. 1, I have shown one circuit as embodied in loops 10 and 11 which are connected to wires 12 and 13 and another circuit having loops 14 and 15 which are connected to wires 16 and 17, respectively. These loops are preferably strips of tinfoil secured to the window panes, but in addition to this form of loop, I may also employ butt or rub contacts on doors, windows, chest lids, or other closures whenever desired. In case of fire the tinfoil strips will be melted, and the closed circuit will be opened which will cause the alarm to be sounded. These various loops may also be connected to doors, 60 chests, and the like, but for purposes of illustration, I have indicated only two such circuits.

75 The battery and electrically operated devices for causing the alarm to be sounded when the normally closed circuit is open, are adapted to be housed in a cabinet 20 which may be provided with a hinged cover 21, as shown in Fig. 2. These devices comprise test switches 23 and 24, a lock switch 25, relays 26 and 27, and an armature 28.

Referring now to the wiring diagram the normally closed circuits may be traced as follows:

Battery A, wire 30, ground 31, ground 32, armature 33, contact point 34, wire 35, wire 16, loops 14 and 15, wire 17, wire 18, wire 12, loops 10 and 11, wire 13, wire 36, stationary contact plate 37, movable contact plate 38, wire 39, coil 26, wire 40 and thence back to battery A. With this arrangement, as soon as the cover of the cabinet is closed, the circuits through the loops are also closed, 85 and the solenoid 26 is energized, thus holding the armature 33 in engagement with the contact point 34 against the force of a retractile spring 41. It is, of course, understood that switches 23 and 24 are normally 90 open and are placed across the lines, as indicated in Fig. 3.

100 Whenever any of the closed circuits are open, either by the breaking of one of the loops, such as by heat from fire, or forced entrance, or opening of the cabinet, then the coil 26 is de-energized, whereupon the armature 33 is drawn upwardly by the spring 41, and into engagement with a contact point 45. This closes the alarm circuit, thus auto- 110

matically causing the alarm 50 to be sounded. The alarm continues to sound even though the normally closed circuit is again closed, such as by the closing of a window 5 which may have been forced open, since the spring 41 holds the armature in engagement with the coil 26.

When the alarm circuit is closed current flows as follows:—Battery A, wire 30, 10 ground 31, ground 32, armature 33, contact point 45, wire 46, alarm 50, wire 47, lock switch 48, movable contact 49, stationary contact 51, wire 52, wire 40, and then back to the battery.

15 If desired, the alarm circuit may be manually opened, after it is once closed, by the operation of a lock switch, indicated generally in Fig. 2 at 25. This may be controlled by a key from a point outside the cabinet. 20 The mechanism actuated by the lock switch may control the operation of an arm 55 to which one end of a link 56 is attached. The other end of the link may be connected to the switch member 48 which carries the rub 25 contact members 49, 57 and 58, respectively. These various contact members, when actuated, are used for shunting the closed circuits, whereby the coil 26 remains energized, thus holding the armature 33 against the 30 contact point 34, and preventing the actuation of the alarm.

When the switch is moved to a position intermediate that shown in Fig. 3 and the dotted line position current flows from the 35 Battery A, through wire 30, ground 31, ground 60, wire 61, stationary contact plate 62, movable contact member 58, switch member 48, movable contact member 57, stationary contact member 63, wire 63, wire 39, 40 coil 26, wire 40 and thence back to the battery.

In order to prevent the surreptitious short 45 circuiting of one of the closed circuits in the line between the cabinet and loops, whereby forced entrance may be obtained without sounding the alarm. I have shown an open circuit of two wires without branches or 50 taps. These wires are in a cable running throughout the building adjacent the closed circuit wires and having the same appearance. This open circuit is independent of the bell circuit but is in series with a relay 27 which is stronger than the relay 26. If a 55 knife is used to remove the insulation from the closed circuit wires with the intention of shorting this circuit to shunt out one of the frangible loops to be thereafter broken. There is an equal chance that the knife will 60 close the open circuit, actuating the relay 27 to draw the armature 33 into engagement with the contact point 45, thus closing the alarm circuit.

When the normally open circuit is closed current flows as follows:

65 Battery A, wire 30, ground 31, ground 32,

armature 33, contact point 34, wire 35, wire 66, then through the short circuiting means indicated by the broken lines in 67, wire 68, relay 27, wire 69, wire 40 and then back to the battery.

70 As soon as the relay 27 is actuated to draw the armature upwardly and away from the relay 26, then engagement with the contact point 34 is broken, whereby the spring 41 functions to hold the armature in engagement with the contact point 45. As soon as the armature is drawn away from the contact point 34, then the coil is deenergized. Accordingly, only a single impulse is given 80 by the relay 27 so that the alarm is sounded even though the closing means, such as a knife blade 67, is immediately removed from the open circuit wires.

It follows then that my invention embodies a closed circuit, an open circuit, and an alarm circuit which is normally open, all of which may be operated from a single source of electrical supply, such as the battery A. The normally open circuit formed by the wires 66 and 67 may, if desired, be 85 connected to a butt, or rub contact adjacent a door, window, or other closure, which would close the contact the same as would any instrument used to cut the wires.

90 The lock switch shown particularly in Figs. 2 and 3 is useful for rendering the system inoperative as when the building is occupied in the day time and freedom of all entrances is desired for making necessary 95 repairs or adjustments, and for enabling the detection of any particular loop which may have been broken. When it is desired to disconnect the alarm circuit, the lock switch is operated to move the contacts 57 and 58 to the position indicated by the dotted line in Fig. 3. When these contact members are in the extreme left hand position, then the circuit to the alarm through the contact member 49 is broken, while the circuit through the members 57 and 58 is also 100 broken. If the lock switch has been moved to make repairs then after such adjustments are made, the switch is returned to the normal position. During the initial movement 105 the contact 49 will engage the plate 51, so that if alarm circuit is completed and in working order the alarm will be momentarily sounded. This sounding amounts to no more than a single stroke or click which 110 informs the operator that the battery is active and thus provides a test for the strength of the current. Then if the switch is turned still farther to the right, contact is made between the members 57 and 58 and the stationary plates 62 and 63 respectively, which 115 shunts the disconnected enclosed circuit and energizes the coil 26, wherefore the armature is moved downwardly against the force of the spring 41 to effect engagement with 120 point 34 which of course stops the alarm.

125 130

Since the lock switch is operable from a point outside the cabinet, then such movements may be effected without opening the lid of the cabinet, and therefore without disturbing the switch embodying the contacts 37 and 38. Then if the switch is moved still farther to the right so as to bring it to the position indicated by the full lines in Fig. 3, the armature will remain in contact with the point 34, even though contact is broken between points 57 and 58 and the points 63 and 62 respectively, provided there is no break in the closed circuit.

If however, there is a break in the closed circuit then when the lock switch is moved to the position shown in the full lines, the alarm will be sounded. To determine then at which point the break is located, the key switch is again moved to the left to bring the contacts 57 and 58 into engagement with contacts 62 and 63 so as to close the circuit through the coil to the armature to the lower position. Then the lid of the cabinet is opened and one of the test switches such as switch 23 is closed, whereupon the lid of the cabinet is again closed and the lock switch is moved to the full line position in Fig. 3. If the alarm is not sounded then the break in the closed circuit is in the loop controlled by the switch 23.

In view of the foregoing description, it will be seen that my invention is well adapted for maintaining an alarm system having a combined open and closed circuit, operable from a single battery, and that the operative devices may be satisfactorily housed in a small cabinet. Further, it will be seen that my invention permits the use of an open circuit, which may be wound in a cable with the wires of a closed circuit, and be so connected with relation to the opposed re-

lays that an attempt to short out the closed circuit would result in the possibility of closing the open circuit, and in either case cause the alarm to be sounded.

45

I claim:

1. In an alarm, a normally closed circuit and a normally open alarm circuit, a source of power, a switch, means whereby said switch may be moved first to close said alarm circuit to test the strength of the source of power, then moved to shunt the alarm circuit to render the alarm circuit inoperative and finally to break the shunt connection, means including a relay connected with the switch and source of power operable to open the alarm circuit when said shunt connection is made and to close the normally closed circuit.

50

2. In combination, a normally closed circuit, a normally open alarm circuit, and an alarm controlled thereby, a source of electric power, a switch having movable contact points, means including cooperating contact points connected to the normally closed circuit and alarm circuit so arranged that both circuits may be first open, the alarm circuit then momentarily closed for testing the condition of said source of power and the normally closed circuit then closed, a relay in 70 the normally closed circuit actuated by said last mentioned closing to open the alarm circuit, means including said switch whereby said switch is then capable of further movement to disconnect the switch from the relay and to reconnect the alarm circuit whereby when the normally closed circuit is surreptitiously broken, the alarm will be sounded.

65

In testimony whereof, I hereunto affix my 75 signature.

GOTTFRIED F. GASSER.
